UNITED STATES PATENT OFFICE

VICTOR H. SEVERY, OF LOS ANGELES, CALIFORNIA

CHECK PROTECTOR

Application filed December 18, 1928. Serial No. 326,764.

This invention relates to a perforating device for perforating checks to render the operations of a forger more difficult. Heretofore such protectors have been employed embodying two plates which are hinged together at one edge and formed on their adjacent faces with teeth that co-operate together to emboss the paper. The teeth of these dies must be sharp and it has been the custom to produce the teeth from a solid plate by a milling operation. This operation is relatively costly as a shop operation and, furthermore, when such a protector is used, it requires considerable force applied to the dies to emboss the paper sufficiently to make the protection effective. Furthermore, where the entire area of the die comes into action at once, it is necessary that the dies have sufficient thickness to render them rigid. This increases the weight of the device and is objectionable particularly where the device is intended to be used as an attachment for a check book.

The general object of this invention is to produce a serviceable protector which can be formed by a stamping operation and constructed of relatively light or thin plate, and at the same time to give the protector a construction which will enable it to operate effectively to perforate the check at the desired point. To this end one of the objects of the invention is to construct the protector with a number of rows of teeth for embossing or puncturing the paper that constitutes the check, and which in use will operate to come into action in succession. In this way a very slight force is necessary to effect the puncturing by each row, but when, however, the actuating movement of the protector is completed, a considerable area of the check will have been perforated or embossed.

A further object of the invention is to construct the protector so that it can be readily secured to a check-book in a position for immediate use and to provide the same with means for holding it in a compact closed or folded position on the book.

Further objects of the invention will appear hereinafter.

50 The invention consists in the novel parts

and combinations of parts to be described hereinafter, all of which contribute to produce an efficient check protector.

A preferred embodiment of the invention is described in the following specification, 55 while the broad scope of the invention is pointed out in the appended claims.

In the drawings:

Figure 1 is a perspective of a check-book and illustrating a device embodying my invention in position to be used to perforate 60 the check.

Figure 2 is a longitudinal section through the perforator showing the same removed from the check-book and in its folded relation. 65

Figure 3 is a section illustrating one of my protectors in its open position and illustrating another embodiment of the invention.

Figure 4 is a detailed view showing a fragment of the perforating die upon an enlarged scale. 70

Figure 5 is a vertical section through the perforating die taken on the line 5—5 of Figure 4. 75

Figure 6 is an edge view of the fragment of the perforating die illustrating Figure 4.

Before proceeding to a detailed description of the device, it should be stated that the device is constructed so that it presents two 80 plates connected together at an edge either by a resilient bow or a hinge connection. The device is constructed so that one of these plates presents a convex face toward the other plate, and one of the plates carries a 85 die disposed transversely across the plate on a line substantially parallel with the attached edge of the plate. In this way when a check is held between the plates and pressure is exerted upon the free edge of the third plate, 90 the dies will commence to operate on the paper toward one edge of the die along the contact line, and this contact line will move progressively toward the free edge of the plate. In this way the rows of the perforating teeth will be brought into operation in 95 succession.

The puncturing or embossing teeth may be formed in any suitable way. For example, the teeth may be formed by pressure or they 100

may be milled or formed by knurling the face of the plate.

Referring more particularly to the embodiment of the invention illustrated, 1 represents a check-book of common form, such as may be readily carried in one's pocket. My protector 2 is adapted to be formed of a thin piece of sheet metal and comprises a base-plate 3 and a die-plate 4, the said plates being connected together preferably by a resilient bow 5 integral with the plates. If desired, a hinge connection may be employed at the point 5 as will be explained hereinafter.

15 The plate 4 is resilient and is constructed so that when unrestrained it will operate to support itself in a raised position away from the base-plate as illustrated in Figure 1, and so that it presents its convex side toward the base-plate. The perforating plate 4 may carry a die-plate, but is preferably formed with a die 6 constructed as an integral part of the perforating plate. This die 6 preferably consists of a plurality of rows 7 of teeth 8 that are struck down from the plate 4 by die, and these teeth are formed preferably of triangular shape (see Figure 6) so that they present a sharp point 9 at their lower end. The die 6 may extend completely 20 across the perforating plate, or, if desired, may extend only a part way across.

The base-plate is preferably provided with means, such as platen 10, of relatively soft material to cooperate with the teeth 8 to puncture the paper of the check 11 laid in the protector. In using the device, the free edge 12 of the perforating plate is pressed downwardly against the check lying on a support, such as a table. When this edge 12 is depressed in this way, the teeth 8 will cooperate with the platen 10 to form a succession of rows of small openings or perforations in the material of the check. If desired, the base-plate 3 may be offset downwardly 25 to form a shallow pocket 13 to receive the platen.

If the material of the protector is very thin, to give it the desirable quality of lightness I prefer to employ means, such as integral ribs 14, formed near the free edge 12 of the perforating plate and extending inwardly toward the attached edge or bow 5. These ribs give this portion of the plate rigidity and make the action of the curved portion in biting through the paper more effective.

Figure 3 illustrates a slight modification of the invention and illustrates the relation of the parts when the protector is in its open position. In this construction the plates are connected by a hinge-joint 15, and also in this embodiment of the invention instead of employing a platen 10 of soft material, I may form a platen 16 by providing perforations 17 in a material of the base-plate to cooper-

ate with corresponding individuals of the teeth 18 in the perforating plate.

If desired, this platen 16 may be raised somewhat by offsetting the material of the base-plate upwardly.

It is obvious also that this type of platen could of course be used with the embodiment of the invention shown in Figure 2, but if great accuracy is necessary for the registering of the teeth with the openings 17, this registering would naturally be superior if used with a positive hinge-joint 15 rather than with a bow-joint 5 which might tend to spring out of its proper position from constant use.

If desired, the forward edge 19 of the base-plate 3 (see Figure 1) may be folded down and under to form a retaining tongue or spring clip 20 to facilitate the attachment of the device to the edge of the check-book.

Any suitable means may be employed for holding the plate or perforating leaf 4 in its depressed position. For this purpose I may employ a small clevis 21 with an extension 22 at one end attached by a pivot pin 23 to the upper side of the plate or leaf 4 at its free edge 12, and this clevis, or clamp, may be formed of a bent plate presenting two jaws 24 and 25, the latter of which may be bent on its inner edge so as to form a lip 26, producing a narrowed throat, or mouth 27 between the jaws. In this case the bent edge 19 is formed with a slight bulge 28 on its under-side (see Figure 2), which operates as a bead for the lip 26 to snap over when the clamp is applied to hold the leaf 4 in its depressed position.

It is obvious that if desired the means for puncturing the check could be formed on the platen if desired instead of on the opposing part that cooperates with the platen to produce the puncturing effect.

What I claim is:

1. A check protector having a base-plate with a platen extending transversely on the same, and having a perforating plate connected to an edge of the base-plate of resilient material and operating to maintain itself normally disposed in a curve with its convex side disposed toward the base-plate, said perforating plate having a die with a plurality of rows of integral teeth struck down from the material of the same and projecting toward the base-plate, said perforating plate operating when depressed at its free edge to engage the platen on a contact line that moves progressively in a direction from the attached edges of said plates toward their free edges so that the rows of teeth cooperate in succession with the platen to perforate the check.

2. A check protector having a base-plate with a platen of relatively soft material mounted thereon and extending transversely and having a perforating plate connected to

an edge of the base-plate, said perforating plate consisting of resilient material and operating to maintain itself normally disposed in a curve with its convex side disposed 5 toward the base-plate, said perforating plate having a die formed therein and consisting of a plurality of rows of integral pointed teeth struck down from the material of the perforating plate projecting toward the platen, 10 said perforating plate operating when depressed at its free edge to engage the platen on a contact line that moves progressively in a direction from the attached edges of said plates toward their free edges so that the 15 rows of teeth cooperate in succession with the platen to perforate the check.

3. A check protector having a base-plate with a platen of relatively soft material mounted thereon and extending transversely 20 and having a perforating plate connected to an edge of the base-plate, said perforating plate consisting of resilient material and operating to maintain itself normally disposed in a curve with its convex side disposed 25 toward the base-plate, said perforating plate having a die formed therein and consisting of a plurality of rows of integral pointed teeth struck down from the material of the perforating plate projecting toward the 30 platen, said perforating plate operating when depressed at its free edge to engage the platen on a contact line that moves progressively in a direction from the attached edges of said plates toward their free edges so that 35 the rows of teeth cooperate in succession with the platen to perforate the check, and means adjacent the free edge of the perforating plate for stiffening the same to facilitate imparting the depressing force to the 40 said die.

4. A check protector having a base-plate with a platen of relatively soft material mounted thereon and extending transversely and having a perforating plate connected to 45 an edge of the base-plate, said perforating plate consisting of resilient material and operating to maintain itself normally disposed in a curve with its convex side disposed toward the base-plate, said perforating 50 plate having a die formed therein and consisting of a plurality of rows of integral pointed teeth struck down from the material of the perforating plate projecting toward the platen, said perforating plate operating 55 when depressed at its free edge to engage the platen on a contact line that moves progressively in a direction from the attached edges of said plates toward their free edges so that the rows of teeth cooperate in succession with 60 the platen to perforate the check, and means for securing the free edges of the said plates together to hold the protector in its folded relation.

5. A check protector having a base plate 65 with a platen extending transversely on the

same and having a perforating plate connected to an edge of the base plate of resilient material and operating to maintain itself normally disposed in a curve with its convex side disposed toward the base plate, 70 said perforating plate having a die with a plurality of projections formed thereupon and extending toward the base plate, said perforating plate operating when depressed at its free edge to engage the platen on the 75 contact line that moves progressively in a direction from the attached edges of said plates toward their free edges so that the projections cooperate in succession with the platen to perforate the check. 80

Signed at Los Angeles, Calif., this 6th day of December, 1928.
